UNITED STATES PATENT OFFICE.

THEODORE HORN, OF CICERO, ILLINOIS.

VENTILATOR.

Application filed June 6, 1921. Serial No. 475,257.

To all whom it may concern:

Be it known that I, THEODORE HORN, a citizen of the United States, and a resident of the city of Cicero, county of Cook, and State of Illinois, have invented certain new and useful Improvements in Ventilators, of which the following is a specification.

My invention relates to improvements in ventilators and more particularly to a ventilator mountable in a window sash, and has for its object the provision of a ventilator mountable in a sash, which is neat in appearance and very easily operated.

Other objects will appear hereinafter.

15 The invention consists in the combinations and arrangements of parts hereinafter described and claimed.

The invention will be best understood by reference to the accompanying drawings forming a part of this specification, and in which,

Fig. 1 is a front elevational view of a portion of the window, showing my ventilator in position therein.

25 Fig. 2 is a section taken on line 2—2 of Fig. 1.

Fig. 3 is a section taken on line 3—3 of Fig. 2, and Fig. 4 is an inverted view of the ventilator.

30 In the drawings I have shown my improved ventilator 10 mounted in position in the side member of a window sash 11, but a ventilator may equally as well be mounted in the top or bottom member or in any part of the window sash, and it may also be mounted in a door sash or through the outer wall of the room or wherever desired.

35 The ventilators are preferably constructed of iron or brass, but may be made of any suitable metal or of wood.

The ventilator comprises a collar 12 which extends through an opening in the sash 11 and has a laterally extending flange 13 which seats in a depression on the interior of the sash 11. The ventilator is fastened in position in the sash by means of screws or similar fastening members 14 which pass through openings in the flange 13. A ventilator opening or slot 15 extends through the collar 12 and establishes communication from the interior to the exterior of the sash or wall, and a closure plate 16 is pivotally mounted in said opening on a shaft 17, supported in the collar 12 and passing through

lugs 18 on said plate. A link 19 pivotally connects said lugs with one end of a lever 20 which is pivotally mounted on a pin 21 fastened in the collar near the bottom wall 22 of the ventilator. The free end of said lever is pivotally connected to the inner end of an operating stem 23 which is slidably mounted in an opening 24 adjacent the opening 15 of the ventilator, and projects beyond the sash, and has a ring 25 fastened on the projecting end, adapted to be engaged by the hand on the inside of the room to operate the plate.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent, is:—

1. A ventilator comprising a sleeve substantially oval shaped which is mountable through a sash and provides an opening which extends from the inside to the outside of said sash and is of the full cross section of the interior of said sleeve, flanges on said sleeve for engaging the inner side of said sash and fastening it thereto, a closing member mounted at the inner end of said sleeve and provided centrally with means projecting into said sleeve, a pivot pin mounted diametrically across said sleeve and extending through said projecting means, means connected to said projecting means and extending through the wall of said sleeve, and manual means attached to said connected means and extending to the interior of the sash for operating said ventilator from the interior of the room.

2. A ventilator comprising a sleeve substantially oval shaped mountable through a sash, flanges on said sleeve for engaging the inner side of said sash and fastening it thereto, a closing member mounted at the inner end of said sleeve and provided centrally with lugs extending into said sleeve, a pivot pin mounted diametrically across said sleeve and extending through said lugs,

a lever extending through the wall of said sleeve and being pivotally mounted on said wall, a link connecting said lever to said lugs, and an inwardly projecting stem slidably mounted through an enlarged portion of the flange and engaging said lever for operating said closing member.

In testimony whereof I have signed my name to this specification in the presence of two subscribing witnesses.

THEODORE HORN.
